PORTABLE RADIO

Ken Kawamura, Katano, Osaka, Japan, assignor to Matsushita Electric Industrial Co., Ltd., Osaka, Japan

Filed Apr. 20, 1973, Ser. No. 353,173

Claims priority, application Japan Oct. 20, 1972

Term of patent 14 years

Int. Cl. D14—03

U.S. Cl. D56—4 B

FIG. 1

FIG. 2

FIG. 1 is a front, top and right side perspective view of a portable radio showing my new design; and

FIG. 2 is a rear, top and left side perspective view.

Portions of the figures are shaded to indicate contrast in appearance, and portions are diagonally lined to indicate transparency.

I claim:

The ornamental design for a portable radio, as shown and described.
